UNITED STATES PATENT OFFICE.

WILLIAM BENJAMIN YATES, OF VENTURA, CALIFORNIA.

HARMONICA.

Application filed October 22, 1924. Serial No. 745,219.

This invention is an improvement in harmonicas.

An object of the invention is the provision of a device capable of attachment to harmonicas of conventional construction having means for controlling the volume and the pitch of the music produced by the instrument.

10 A further object of the invention is the provision of a device of this character wherein the means for controlling the volume of music also serves as a handle for supporting the instrument in operative position.

With these and other objects in view, as 15 will appear as the description proceeds, the invention consists in the novel features of construction, combinations of elements and arrangements of parts hereinafter to be fully described and claimed.

20 A full and complete understanding of the invention may be obtained from a consideration of the following detailed description, taken in connection with the accompanying drawing forming a part of the specification, 25 it being understood that while the drawing shows a practical form of the invention, the latter is not to be confined to the showing thereof, but may be changed or modified so long as such changes and modifications mark 30 no material departure from the salient features of the invention as specifically pointed out and claimed.

In the accompanying drawing wherein 35 similar reference characters designate similar parts in the views,

Figure 1 is a perspective view of the device as applied to a harmonica of conventional design,

40 Figure 2 is a vertical sectional view taken on the line 2—2 of Figure 1, and

Figure 3 is a horizontal sectional view.

In the specific embodiment of the invention illustrated in the accompanying drawing the numeral 1 designates a harmonica 45 of usual construction from which the protecting sides (not shown) have been removed to adapt it for association with the amplifying and tone controlling device about to be described.

50 This device comprises a substantially triangular casing having a top 3 and bottom 4, with converging sides 5 which terminate at one end to provide the circular opening 6.

The top 3 and bottom 4 are extended on 55 the side opposite to the aperture 6 and inwardly bent as at 7 to form lips to engage

the spaced plates 8 of the harmonica 1 which is supported midway between the top and bottom by means of rivets 9 traversing the laterally extending ears 10.

An elongated tubular member 11 extends from within the chamber 2 through the aperture 6 and has its inner end enlarged as at 12 and apertured as at 13 to receive the upper hollow end 14 of the supporting and volume controlling handle 15 which has bearing in aligned apertures 16 in the top 3 and bottom 4.

The end 14 is closed at 16^a, and is apertured at diametrically opposite points to provide a passageway 17 through which air from the chamber 2 may pass into the tubular member 11. It will be observed that the volume of air passing through the opening 17 and the tube 11 may be positively controlled by manipulation of the handle 15 and may be entirely cut off by turning the handle until the passageway 17 is arranged transversely of the tube.

A second tubular member 18 which is open at its inner and outer ends is arranged to telescope within the tube 11 and permits variation of the pitch of the music as the length of the combined tubes 11 and 18 is varied by longitudinal movement of tube 18 with respect to the tube 11. A handle 18^a is provided on the tube 18.

In the practice of the invention, the device is held in one hand by means of the handle 15 and the lips of the operator engage the extensions of the top and bottom or in other words the mouth of the operator or player is presented to the harmonica in the ordinary manner.

When the operator blows into the instrument the air passes through into the amplifying chamber 2 from which its only outlet is through the passageway 17, into the tubes 11 and out through the tube 18, and the volume of the sound may be controlled by slight rotation of the handle 15 which may be conveniently turned by the hand supporting the instrument. It is obvious that by varying the registration of the passageway 17 with the chamber 2 and the tube 11, that the volume of air that may act on the reeds of the harmonica is varied and in this way the volume of the musical sound produced by the harmonica is controlled and varied. The pitch of the music may be varied at will by moving the tube 18 in and out of the tube 11 in the same manner as the

pitch of music from a trombone is controlled, that is, by increasing or decreasing the combined length of the tubes 11 and 18.

It will be noted that the tubes 11 and 18, together constitute an extensible tone column and the handle 15 constitutes a means for controlling communication between the casing and the tone column. The outer end of the tube 18 is preferably flared or bell-shaped, as shown. Of course the resonance of the reeds is also depended upon to produce the music but the character and quality of the music and especially its pitch is varied by varying the length of the tone column constituted by the tubes 11 and 18.

Having thus fully described the invention, I claim as new and desire to secure by Letters Patent:

1. A device of the class described, comprising a substantially triangular shaped casing including a top, a bottom, and a pair of side walls, means for supporting a harmonica between said top and bottom at one side of the casing, a tubular member secured to and extending from the casing and having an enlarged portion, a rotatable handle having a hollow closed end extending through the top, the bottom, and said enlarged portion, and having a transverse passageway therethrough for alignment with said tubular member, the turning of the handle operating to vary the extent of communication between the casing

and the tubular member, and a second tubular member open at both ends and telescopically mounted within said first mentioned tubular member.

2. A device of the class described, comprising a casing including a top wall, a bottom wall, a pair of converging side walls and an open side, means for supporting a harmonica between said top and bottom walls to close said open side, a tubular member extending from the casing and having an enlarged portion, a handle having a hollow end extending through the top walls and bottom of said casing through the enlarged portion of said tubular member, means whereby passage of sound through said member is controlled by said handle, and a second tubular member telescopically mounted within said first mentioned tubular member.

3. A device of the class described comprising a casing having an open side, means for supporting a harmonica by the casing in closing relation to said open side, a tubular member extending from the casing and having an enlarged portion, a handle extending through the casing and said enlarged portion, means whereby passage of air through said casing is controlled by said handle, and means cooperable with said member to vary the pitch of sound emanating from the harmonica.

WILLIAM BENJAMIN YATES.
